UNITED STATES PATENT OFFICE

ROBERT N. WEST, OF MAPLEWOOD, NEW JERSEY

MACHINE FOR PRESSING FABRICS

Application filed March 4, 1931. Serial No. 520,017.

This invention relates to a combined press and reciprocatory ironer, particularly adapted for use in laundries and garment pressing establishments and has for its principal objects the provision of a compact and inexpensive machine wherein the work is preferably held in a horizontal plane throughout the ironing operation and preferably a relative reciprocatory motion is provided between the heated chest and the buck, either when employing the machine as a press or as a reciprocatory ironer, besides other advantages hereinafter set forth. In the accompanying drawings, in which I have illustrated a preferred embodiment of my improved mechanism;

Figure 1 is a vertical section, partly in elevation of such mechanism;

Fig. 2 is a front elevation of the same mechanism;

Fig. 3 is a detail elevation partly in section of a modified form of counter balanced buck;

Fig. 4 is an end elevation, partly in section, of a still further modification, wherein means are provided for transversely reciprocating the heated chest during the pressing of the work, the chest being shown elevated; and Fig. 5 is a similar but fragmentary view of the same mechanism showing the chest lowered into contact with the buck.

Referring to the drawings and the construction shown therein, the reference numeral 1 designates vertical end frames which are adapted to be secured to a suitable base or support and 2 are stay rods securing the opposing end frames together. Between said end plates is a rotary buck-supporting member, the same comprising opposing spiders 3 which are keyed to a shaft 4 that is mounted at its respective ends in bearings in said frames 1. An index plate 5 is rigidly secured to one end of said shaft 4, the same being apertured at intervals and spring-pressed index pins 6 are adapted to project into apertures 7, spaced at 90° intervals around said index plate, whereby the different positions of said buck-supporting spiders can be accurately controlled and predetermined.

Bucks 8 are carried by said spiders. Each

buck has a saddle 9 cast integral therewith which is bolted to a corresponding saddle 10 of a weight member 12 so as to tightly embrace a sleeve member loosely mounted on the buck supporting shaft 11 interconnecting the opposing spiders and centrally positioned thereon between the opposing collars that splined or otherwise rigidly secured to said shaft whereby said buck can oscillate freely on said shafts 11 and is continually maintained in a horizontal position during the rotation of the spiders.

At the top of the machine is a heated chest 13, which has hollow guard members 13' secured thereto, the same being spaced from and projecting across the ends of said chest and serving to prevent contact between the hands or arms of an operator and the heated chest during the operation of the machine, besides also serving to protect the face and body of the operator from heat radiated from said chest. The chest is provided with terminal extensions or lugs 14 which are apertured to receive piston rods 15 that are carried by pistons reciprocating within air or steam cylinders 16, the latter having ports 17 and 18 for the alternate admission of fluid effecting the vertical reciprocation of said piston rods. At the upper ends, said piston rods are threaded to receive nuts *a* and *b* respectively, which, as shown, are so positioned on said rods that if desired, in those cases where applied steam or air pressure is not deemed necessary, the weight of the chest may be carried by the lower nuts *b* when the chest is elevated, but when the chest is in its lowermost position and in contact with a buck, the arms are moved to an intermediate position between said nuts, so that the chest rests by gravity upon a buck and is not forcibly held thereon by the upper nuts *a*. Said chest, if steam heated, is provided with an inlet and outlet conduit *c* for the introduction of and withdrawal of steam from said chest in the well known manner, although obviously an electrically heated chest may be employed, if desired.

As shown, the rotation of the bucks into their various indexed positions is accomplished manually by means of handles *d* pro-

vided for this purpose and the vertical movement of the steam chest is accomplished by means of a lever or pedal adapted to be operated by hand or by foot pressure, such lever or pedal controlling the admission and release of the fluid pressure medium from the pressure elevating cylinders 16.

In the construction shown in Fig. 3, the enlarged balancing weights 12', corresponding generally to the weights shown in Figs. 1 and 2, are employed, said weights having downwardly projecting terminal lugs α that have flat bearing surfaces, which while preferably of the same thickness as the thickness of the weight from which they project, may obviously be greatly reduced in width since they are adapted to rest directly on the shaft 4 when each buck rides into its uppermost position under the chest 13 and thereby the pressure imparted by the steam chest, when resting on such buck, is imparted directly to and borne in the first instance by said shaft 4, thus relieving the shafts 11 from excessive central stresses. Obviously, however, as each buck leaves its uppermost position and commences to rotate between the frames 1, the lugs α slide off and out of engagement with the shaft 4 and will not re-engage the same until such buck has again attained its uppermost position beneath said chest 13.

In the construction shown in Figs. 4 and 5, I have provided means for causing a slight reciprocatory movement of the chest across the buck in a direction parallel to the axis of the shafts 11, while the chest is in contact with the work carried by the bucks, and thereby an extremely smooth sheen or finish is imparted to such work similar to that obtained when ironing with friction ironers or by hand. This latter construction is essentially the same as that shown in Figs. 1 and 2, except that the lugs 14' are provided with slots e , which admit of the slight transverse movement of the chest with respect to the bucks 8. Such movement is positively accomplished by means of impulses imparted to the opposite ends f of said chest by the piston rods 20 that are carried by pistons within fluid pressure cylinders 21 which are rigidly mounted on the vertical piston rods 15. As shown, when one of said piston rods 20 is projected to the limit of its stroke, the other is retracted. Preferably the piston rods 20 are continuously operated in opposite directions during the ironing operation, irrespective of whether the heated chest is in an elevated or lowered position, as thereby the possible displacement of the work carried by the bucks 8, as might otherwise occur, due to excessive frictional engagement of the chest and buck, were the chest to be first lowered into contact with the work prior to the commencement of the transverse reciprocation of the chest, is avoided. In order to interconnect the piston rods 15 so as to maintain the same

in parallelism, I provide a stay bar 22 which is secured at its opposite ends to the top ends of said piston rods 15. Said fluid pressure cylinders 21 which are well known equipment for supplying fluid pressure for various purposes, are provided with outlet ports g in the manner well known for the admission and escape of fluid during the respective strokes of the piston.

My improved mechanism renders it possible to not only very substantially increase the output of each operator as compared with the output per operator on other machines, owing not only to the speed and facility with which the work can be handled as well as due to the increased efficiency of the operators because of the better protection against the radiated heat from the chest which is afforded by this construction.

Having thus described my invention, what I claim and desire to obtain by United States Letters Patent is:—

1. In a pressing machine, the combination comprising a rotatable pad carrying support, a plurality of swivelled pads carried thereby, gravity responsive means for continually maintaining said pads approximately in a horizontal position during the rotation of said support, a heated chest associated with said support and adapted to be brought into pressure engagement with an article to be pressed that is carried by a pad when the latter is positioned immediately beneath said chest, and means for moving and locating a pad carrying an article to be pressed beneath said chest.

2. In a pressing machine, the combination comprising a rotatable pad carrying support, a plurality of swivelled pads carried thereby, gravity responsive means for continually maintaining said pads approximately in a horizontal position during the rotation of said support, a heated chest associated with said support and adapted to be brought into pressure engagement with an article to be pressed that is carried by a pad when the latter is positioned immediately beneath said chest, means for moving and locating a pad carrying an article to be pressed beneath said chest and means for effecting relative to and from movement of the chest and a pad positioned immediately beneath the same.

3. The sub-combination comprising a rotatable pad carrying support, a plurality of pad carrying buck members carried thereby and in swivelled relation thereto and a weight member associated with each buck for normally maintaining the same in a horizontal position.

4. The sub-combination comprising a frame, a shaft mounted therein, a rotatable buck carrying support mounted on said shaft, buck members swivelled on said support in spaced relation with each other, and weight members associated with each buck, said

weight members being normally adapted to rest upon said shaft when the buck member associated therewith is in its uppermost position and also to normally maintain such buck in a substantially horizontal position during the revolution of said buck carrying support.

5. The combination comprising a frame, a rotatable buck carrying support mounted thereon, a reciprocatable heated chest carried by said frame, buck members mounted on said support, means for effecting the movement of said chest towards and from one of said bucks when the latter is positioned beneath the chest and means for effecting relative transverse reciprocation of said chest and such buck.

10. In an ironing machine, the sub-combination comprising a rotatable buck carrying support, bucks carried thereby, a vertically movable heated chest associated with said support and independently mounted with respect thereto, means for causing said chest to move downwardly and exert pressure against a buck carried by such support when brought into position beneath such chest and means for effecting relative lateral reciprocation of such chest and a buck during the pressure engagement thereof.

15. In an ironing machine, the combination comprising a frame, a rotatable buck carrying support mounted thereon, a plurality of bucks carried by said support, a vertically reciprocatable heated chest carried by said frame and means, including reciprocating pistons, mounted independent of said buck carrying support, for effecting lateral reciprocation of said chest when the latter is in pressure engagement with an article to be pressed which is carried by a buck when the same is positioned beneath said chest.

20. In a combination press and ironer, the combination comprising a supporting frame, a rotatable buck supporting member journaled in said frame, a plurality of bucks mounted at spaced intervals around the periphery of said buck supporting member, means for maintaining said bucks normally in a horizontal position, a steam chest supported on said frame and arranged to move vertically, means for effecting such movement of said chest including cylinder and piston members, means for effecting the transverse reciprocation of said chest including cylinder and piston members, and said latter cylinders being adapted to move vertically with the movements of the said chest and means whereby the operator of the machine can control the movements of said chest, as desired.

25. In a pressing machine, the sub-combination comprising a buck member and a chest member which latter is adapted to be heated and means to move the chest member downwardly toward said buck member when the latter is positioned immediately beneath and

in proximity thereto, means for causing pressure contact between said chest member and an article to be ironed when mounted on said buck and means for effecting the relative to and fro motion of the buck and chest while the chest is in its lowermost position and in contact with an article to be ironed positioned on said buck whereby frictional pressure ironing of such article can be accomplished.

30. In a pressing machine, the sub-combination comprising a rotatable buck carrying support, a plurality of bucks mounted peripherally thereon at spaced intervals from each other and means for normally maintaining said bucks in a horizontal position during the rotation of said support.

Signed at New York, in the city, county and State of New York, this 27th day of February, 1931.
